UNITED STATES PATENT OFFICE.

FERDINAND BURCHARTZ, OF NEW YORK, N. Y., ASSIGNOR TO BURCHARTZ FIRE PROOFING COMPANY, INC., OF NEW YORK, N. Y., A CORPORATION OF NEW YORK.

FLOOR AND CEILING CONSTRUCTION.

1,142,486.

Specification of Letters Patent. Patented June 8, 1915.

Original application filed October 12, 1910, Serial No. 586,608. Divided and this application filed March 11, 1912. Serial No. 682,872.

To all whom it may concern:

Be it known that I, FERDINAND BURCHARTZ, a citizen of the United States, and a resident of the borough of Manhattan, city, county, and State of New York, have invented certain new and useful Improvements in Floor and Ceiling Construction, of which the following is a specification.

My invention relates to floor and ceiling constructions in which open ended or hollow blocks are incorporated and has for its object to arrange said blocks in spaced relation to each other with the side walls thereof spaced from the open ends of the blocks; or in other words with the axes of adjacent blocks extending at an angle to each other, to form two way or intersecting channels for the accommodation of a coalescent material and of reinforcing rods, if desired.

My invention also contemplates the provision of a means for closing the open ends of the blocks against the entrance of the coalescent material, which closing means together with the side walls of the blocks form the walls of the channels.

My invention will be fully described hereinafter and the features of novelty will be pointed out in the appended claims.

The present application is a division of one filed by me in the United States Patent Office on October 12, 1910, Serial No. 586,608.

Reference is to be had to the accompanying drawings, in which—

Figure 1 is a cross sectional view of one form of block, which may be used in my construction; Fig. 2 is a cross section of a portion of my improved floor or ceiling construction and Fig. 3 is a plan view thereof before the coalescent material has been introduced.

The particular form of block which I have used to illustrate my invention comprises an open ended body 10, the one wall 11 of which is thickened and provided with a channel 12 extending in a direction parallel with the longitudinal axis of the block as clearly shown in Figs. 1 and 2. This channel 12 as shown in the drawings serves to accommodate a portion of the means for closing the open ends of the body 10, or more specifically the one end of closing

plates 13 which project into opposite ends of said channel for a certain distance and then extend at substantially right angles to 55 said channel to completely close or cover the open ends of the said body 10. The closing plates are preferably made of metal so as to be easily manipulated, although any other suitable material may be used, if 60 desired, and said plates instead of being solid may be made of wire mesh or other foraminated material. Instead of having two separate plates 13, a single plate may be substituted and passed entirely through 65 the channel 12 so as to have its opposite ends projecting beyond the opposite ends of said channel. These projecting ends may then be bent at substantially right angles to extend over and cover the open ends 70 of the body 10, or if desired, any other of the forms of closing means either of the kind shown in my parent application above referred to or of any other kind suitable for the purpose may be substituted, if desired. The channel 12 is preferably a trifle wider than the width of the axial opening 12^a of the body 10 so as to be capable of accommodating a closing medium which is a trifle wider than said axial opening 12^a. 80 Similarly the portions of the closing medium which extend over the open ends of the body 10 should preferably extend below the inside surface of the wall of the body which is opposite to the wall in which the channel 11 is located. Thus, when the closing medium is in position, the entire periphery of the axial opening 12^a will be overlapped and the open ends of the body 10 thus completely closed against the admission of concrete or other coalescent material. In the form of block which I have used in illustrating my invention the body 10 is provided with a preferably integral projection 14 extending lengthwise or longitudinally of the wall in which the channel 11 is formed. This projection 14 is also provided with a channel 14^a extending parallel to the channel 11 and preferably entirely through the projection 14 in a longitudinal direction. The cross-sectional width of the said projection is preferably somewhat less than the cross-sectional width of the body 10 and is preferably ar-

95

100

ranged in the center of said body which thus extends equally to each side thereof. The blocks may also be provided with flanges 15 which extend parallel with the 5 axis of the block at opposite lower edges of the body 10 and serve as one means for forming a bottom for the channels referred to hereinafter. It is to be understood that this projection 14 may be omitted and further that this particular form of block is 10 only one of many which may be used in constructing a floor or ceiling according to my invention. It will readily be seen that for instance any of the forms of block illustrated in the parent application above referred to may be substituted in carrying out my arrangement as described herein-after.

In constructing a floor or ceiling according to my improvement the blocks are set 20 up on the customary temporary scaffolding in such a manner that the longitudinal axes of adjacent blocks extend at substantially right angles to each other. In other words, 25 the side walls of one block are located between and opposite to the open ends of two adjacent blocks as can clearly be seen by referring to Fig. 2 of the drawings and so as to be spaced from said open ends, the flanges 30 15 if used serving as a medium for spacing the blocks and as a bottom for the space therebetween. In this condition the closing means and side walls of the blocks will form the vertical walls of channels 16 which cross 35 each other and extend preferably parallel to each other in two directions. Reinforcing rods 17 may be placed in these channels 16 so as to extend lengthwise thereof, said rods being anchored in and supported by the 40 walls of the building in the usual manner. After the reinforcing rods 17 have been placed in position concrete or other coalescent material 18 is introduced into said channels so as to fill the same and in some 45 cases also to cover the upper surfaces of the blocks. The said coalescent material will firmly bind the blocks into a solid monolithic structure and will form girders or beams of great strength and rigidity. If 50 the specific form of block illustrated in the drawings is used the projections 14 will interrupt the coalescent material 18 which covers the upper surfaces of each block to each side of its projection 14. Some of the 55 coalescent material will enter the channels 14 so that the resulting girder or beam of coalescent material will have substantially the form of a T in cross section and will consequently have a maximum power to resist strains of any kind. The coalescent material is prevented by the end closing 60 means from reaching the interior of the bodies 10 and also serves to securely lock said end closing means in operative position.

65 A very light and extremely strong and

durable floor or ceiling of great carrying and resisting power is secured with my construction, which floor or ceiling is also absolutely fire proof.

As before stated the particular form of 70 block shown herein has only been adopted to illustrate the invention and is only one of many forms which may be used in carrying out my arrangement. It is also to be understood that means or devices other than 75 the flanges 15 may be used to form bottoms for the cross-wise extending channels 16.

The principal idea embodied in the present invention is that of placing open ended blocks at an angle to each other and spaced 80 apart in such a manner that the side walls of the blocks together with the means for closing said open ends form the vertical walls of channels which cross each other and serve to accommodate reinforcing rods and 85 coalescent material as described.

Various changes in the specific form and arrangement shown and described may be made within the scope of the claims without departing from the spirit of my invention. 90

I claim:

1. In a floor or ceiling construction, a plurality of open ended blocks spaced from each other to form intersecting channels, and arranged with the axes of adjacent 95 blocks extending at an angle to each other, a coalescent material in said channels and means for preventing said coalescent material from entering the interior of each block. 100

2. In a floor or ceiling construction, a plurality of open ended blocks spaced apart to form intersecting channels, and arranged with the axes of adjacent blocks extending at an angle to each other, closures for closing the open ends of the blocks, and adapted together with the side walls of the blocks to form the walls of said channels and a coalescent material in said channels. 105

3. In a floor or ceiling construction, a plurality of open ended blocks spaced apart to form intersecting channels, and arranged with the axes of adjacent blocks extending at an angle to each other, closures for closing the open ends of the blocks, and adapted together with the side walls of the blocks to form the walls of said channels, reinforcing rods in said channels and a coalescent material in said channels covering said reinforcing rods. 115

4. In a floor or ceiling construction, a plurality of open ended blocks arranged with the axes of adjacent blocks extending at angles to each other and with a side wall of a block spaced from the open end of an adjacent block, closures arranged to close the open ends of said blocks and adapted together with said side walls to form the walls of channels, means for spacing said blocks apart and arranged to form the 125 130

bottoms of said channels and a coalescent material in said channels.

5. In a floor or ceiling construction, a plurality of open ended blocks arranged with the axes of adjacent blocks extending at angles to each other and with a side wall of a block spaced from the open end of an adjacent block, closures arranged to close the open ends of said blocks and adapted together with said side walls to form the walls of channels, flanges extending along said blocks for spacing them apart and for forming the bottoms of said channels and a coalescent material in said channels.
- 10 6. In a floor or ceiling construction, a plurality of open ended blocks arranged with the axes of adjacent blocks extending at angles to each other and with a side wall of

a block spaced from the open end of an adjacent block, closures arranged to close the open ends of said blocks and adapted together with said side walls to form the walls of channels, flanges extending along said blocks for spacing them apart and for forming the bottoms of said channels, reinforcing rods in said channels and a coalescent material in said channels covering said reinforcing rods.

20 In testimony whereof I have hereunto set my hand in the presence of two subscribing 25 witnesses.

FERDINAND BURCHARTZ.
